AUTOMATIC VOLTAGE REGULATOR

Michael Debrey, Burlington, Iowa

Application January 22, 1937, Serial No. 121,879

4 Claims. (Cl. 200—111)

This invention relates to an improved automatic voltage regulator and is more particularly intended for use with generators of various types.

5 One object of the invention is to provide a voltage regulator which will be operable for automatically short circuiting a regulator resistance in the field circuit of a generator exciter whereby intermittent increased excitation of the generator by said exciter will be provided so that sudden loads on the generator will not cause impairment of operation of said generator.

10 Another object of the invention is to provide an automatic voltage regulator which will be simple in construction and capable of easy installation, and which will not require the use of a field relay or other supplementary attachments.

15 A further object of the invention is to provide a device of this nature which will be of the vibrating contact type and which will embody a core which is operatively responsive to the frequency of alternating current developed by the generator for vibrating the contacts employed.

20 A further object of the invention is to provide an automatic voltage regulator wherein means are embodied for permitting adjustment of the contacts so that the operation of the device may be effectively regulated.

25 And the invention seeks, as a still further object, to provide an automatic voltage regulator employing an inductively coupled secondary coil which will be energizable, when the generator is under load, for permitting a time lag in the opening and closing of the contacts.

30 Other and incidental objects of the invention, not specifically mentioned in the foregoing, will render themselves apparent during the course of the following description.

35 In the accompanying drawings:

40 Figure 1 is a diagrammatic view of my improved voltage regulator and showing certain of the working parts thereof in elevation.

45 Figure 2 is a fragmentary end view of the device, portions thereof being broken away and shown in section.

Figure 3 is a top plan view of the device.

Referring now more particularly to the accompanying drawings, wherein like numerals of reference will be seen to designate like parts throughout the several views, the numeral 1 indicates the base of my improved voltage regulator. The base is preferably rectangular in general contour and is formed of suitable insulating material. It should be understood that the base 55 may be of any desired shape, depending upon

the requirements of individual installations, and is adapted to be secured to a panel or wall 2, preferably at right angles thereto, by bolts formed integral on blocks 3 which are mounted on the base in parallel spaced relation to each other, and which are preferably formed of light weight metal.

Carried on the base 1 and disposed in parallel spaced relation to the innermost block 3, is a yoke 4 which includes a bight portion 5 having 10 an extended portion 6 terminating in a bolt which, like the bolts formed on the blocks 3, extends into the panel 2. The yoke also includes upstanding arms 7 and 8 which are spaced along the length of the bight portion 5 and are adapted to receive, at their corresponding upper end portions, pivot bolts 9 and 10 which are disposed in horizontal alinement in opposed relationship. The yoke is adapted to have pivotally mounted therein a contact supporting member indicated 15 in general by the numeral 11 and which includes a relatively long lever portion 12 and a relatively short arm 13. The lever portion 12 is adapted to extend above the base 1 normally in parallel spaced relation thereto and terminates 20 near the end of the base. The lever portion is provided with an eye bolt 14 which receives the lower end of a coil spring 15. The upper end of the coil spring 15 is supported by an adjusting bolt 16. The adjusting bolt 16 is mounted 25 in a relatively long overhanging block 17 which is mounted on the panel 2 by means of a screw 18 which extends through the panel and into the inner end portion of said overhanging block 17. The adjusting bolt may be rotated in a 30 clockwise or counterclockwise direction for raising or lowering the bolt with respect to the lever portion 12 and resiliently tightening or loosening the tension of the spring 15. The bolts 9 and 10 are, of course, adjustable for mounting 35 the contact supporting member 11 so that it will be firmly mounted and yet free to rock between the arms 7 and 8 of the yoke.

The contact arm 13 is adapted to have adjustably mounted thereon, at its upper end, a 40 contact screw 19 which terminates in a contact 20. The contact screw is threaded through the upper end of the arm 13 and is normally held in a set position by a lock nut 21. An adjusting screw 22 is threaded through the arm 13 below 45 the contact screw 19 and has a head 23 thereon. The screw 22 is normally held in a fixed position by means of a lock nut 24.

Mounted on the base 1 and disposed between the yoke 4 and the blocks 3 is an upstanding 50

arm or standard 25 which has a base portion 26 and a relatively long arm 27 which is reduced in thickness throughout the major portion of its length. The arm 27 is adapted to be disposed in longitudinal alignment with the relatively short arm 18 of the contact supporting member 11 and is also adapted to be secured to the base portion thereof by means of a locking screw 28. Carried on the standard and secured to the relatively long arm 27 is a relatively long spring contact member 29 which is adapted to support at its upper end portion a contact pin 30. The contact pin 30 extends at opposite sides of the upper end portion of the relatively long spring contact member and, at one side of said member, extends through an opening 31 in the arm 27 to terminate in a head 32, which head limits swinging movement of the spring contact member away from the arm 27. At the opposite side of the spring contact member, the pin 30 extends at right angles to said member and terminates in a contact 33 which is disposed in alignment with the contact 28 and is adapted to cooperate therewith. In order to permit adjustment of the spring contact member 29, I provide a spring adjusting screw 34. The spring adjusting screw is adapted to be screwed through the lower end portion of the relatively long arm and to abut, at its free end, the under surface 30 of the spring contact member 29.

Associated with the contact supporting member 11 and connected with the lever portion 12 thereof near the yoke 4 is a plunger rod 35. As best seen in Figure 1 of the drawings, the plunger rod extends upwardly through the base, through the base portion of the standard 25, and is pivotally connected with said lever portion 12. The lower end of the plunger rod 35 is secured to a solenoid plunger 36 which is adapted to be disposed within a primary magnet coil 37 and a secondary magnetic coil 38. The lower end portion of the solenoid plunger is provided with a guide pin, indicated in dotted lines at 39, which is disposed in a guide socket 40 carried at the lower end of the plunger. Further description of the construction and operation of the primary and secondary magnet coils and their association with the rest of my invention will follow hereinafter.

50 On the base 4, at the opposite side of the yoke from the standard 25, there is mounted a spring supporting post 41 including a base 42 and an upstanding arm 43. The base 42 and the arm 43 are connected by means of a connecting screw 44. Carried on the arm 43 and extending upwardly throughout its length is a spring 45 which is turned upon itself at its upper end to define a stop face 46. The spring is connected with the arm 43 by means of a relatively small screw 47 and said spring is adjustably mounted on said arm 43 by means of a bolt 48. The arm 43 is adapted to be in longitudinal alignment with the relatively short arm 18 of the contact supporting member 11 and the stop face 46 is adapted to confront the head 32 of the adjusting screw 22 but normally said head and stop face are disposed in close spaced relation to each other and not in direct interengagement. The spring 45 and the stop face 46 thereof will, however, prevent too great swinging movement of the relatively short arm 18 away from the standard 25.

70 In Figure 1 of the drawings, I have shown diagrammatically the circuit arrangement of my improved automatic voltage regulator and

by again referring to this figure, it may be seen that the numeral 49 indicates, in general, a generator exciter including a field coil 50 and an armature 51. The generator exciter also includes in the circuit a field exciter rheostat 52. The exciter 49 is electrically connected with a generator 53 which, in the present instance, is an alternator for generating alternating current of preferably low frequency. The alternator includes a field winding 54 and an armature 55, 10 and said alternator also includes a field rheostat 56. The alternator and exciter may be built in one casing, or separately, as preferred. The alternator is connected with the primary magnet 37 by means of conductors 57 and 58 and the contacts 20 and 33 are connected to opposite terminals of the exciter field rheostat by means of conductors 59 and 60. A condenser 61 is preferably shunted across the contacts 20 and 33 so as to prevent pitting such as would be caused by repeated sparking of the contacts 20 and 33.

The secondary magnet coil 38 has a variable resistance or rheostat 62 shunted thereacross and said rheostat includes a resistance 63 and a variable arm 64. The rheostat has one end thereof connected to the arm 64 and to the end of the magnetic coil to which said arm is connected, by means of a conductor 65. It will be seen that the portion of the rheostat 62 which is not in use will be short circuited and will be of no inductive effect.

In use, after my improved voltage regulator has been installed, the operation will be as follows: The alternator 53 will supply current 35 through the conductors 57 and 58 to the primary magnet coil 37 for energizing said coil. As the coil is energized, the solenoid plunger 36 is raised within the primary and secondary magnet coils 37 and 38 for shifting the plunger rod upwardly 40 and rocking the lever 12 of the contact supporting member 11 upwardly so that the relatively short arm 18 of the contact member will be rocked away from the relatively long arm 27 of the standard 25. The contacts 20 and 33 will 45 be separated and the exciter field rheostat 52 of the exciter 53 will be retained in the circuit so that the output of the exciter 53 will be reduced, with consequent lowering of the voltage of the alternator 53. As the voltage of the 50 alternator 53 is lowered, the energization of the primary and secondary magnet coils 37 and 38 will be reduced so that the solenoid plunger 36 will be permitted to drop. The plunger rod 35 will, of course, drop and will rock downwardly 55 the lever 12 of the contact supporting member 11 so that the relatively short arm 18 will be swung toward the standard 25 for engaging the contacts 20 and 33. When the contacts 20 and 33 are engaged, the exciter rheostat 52 will be 60 short circuited so that the full output of the exciter will be impressed upon the alternator with the result that the alternator voltage will be increased for again raising the solenoid plunger and breaking the circuit between the contacts 20 and 33 and again introducing the field rheostat into the circuit. It should be understood that the making and breaking of the contacts 20 and 33 will be done at a high rate of speed so that it may be said that the contact 70 supporting member provides a vibrating connection between said contacts 20 and 33. The contact plunger 36 will be caused to move upwardly and downwardly at the frequency of the current generated by the alternator so that the con- 75

tacts will be caused to make vibrating connection at this frequency.

The secondary magnet coil 38, which is only inductively coupled with the primary magnet coil 37, permits a slight time lag between the contacts 20 and 33. The contacts 20 and 33 will lag, or rest, at low frequency in both the open and closed positions. By low frequencies is meant frequencies under one hundred and thirty cycles 10 while by high frequencies is meant frequencies above one hundred and thirty cycles. When the device is being used for high frequency work, the secondary magnet coil will not be employed as the primary magnet coil 37 will function with 15 complete success. If desired, the secondary coil may be eliminated at all frequencies but it has been found that said secondary magnet coil increases the efficiency of the device at low frequencies. The response of the secondary magnet coil 38 is, of course, controlled by the rheostat 62.

In view of the fact that the contact 33 is mounted on the spring contact member 29, a proper amount of lag during the opening and closing of the contacts will take place so that the exciter will operate at full output for a long enough space to permit the alternator to again pick up sufficient current to energize the primary coil for again breaking the circuit and preventing over-excitation of the generator.

Ordinarily, the relatively short arm 13 is in such a position relative to the spring supporting post 41 that the head 23 of the adjusting screw 22 will be out of engagement with the stop face 46 of the spring 45. If, however, too great excitation of the alternator should take place, the solenoid plunger 36 will shift upwardly far enough for engaging the head 23 with the spring 45. Said spring will, therefore, prevent too great shifting movement of the contact supporting member 11. The spring 15 which is connected to the lever 12 and to the adjusting bolt 16, will cooperate with the solenoid plunger 36 for retaining the contacts 20 and 33 in proper operative position. The spring adjusting screw 34 40 may, of course, be adjusted for regulating the amount of lag to take place between the contacts 20 and 33. It is believed that the construction and operation of my improved automatic voltage regulator will be clearly understood from the foregoing so that further description is deemed unnecessary. It should also be understood that minor changes in the construction may be made without departing from the scope of the invention.

Having thus described the invention, what I claim is:

1. In an automatic voltage regulator, a base, a yoke carried by the base, a contact supporting member carried by the yoke and having a relatively short arm and a contact, a standard carried by the base and having a relatively long arm, a relatively long spring contact member carried by the standard, a contact on said contact member and being adapted to cooperate with 60 said first mentioned contact, said contact sup-

porting member including a lever, a magnet coil, a solenoid plunger carried by the magnet coil and having a plunger rod connecting said solenoid plunger and said lever, a spring supporting post carried by the base, and a spring carried by the 5 post and limiting rocking movement of the contact supporting member.

2. In a voltage regulator, supporting means, a voltage coil carried by the supporting means, a core movably mounted within the coil, a yoke 10 on the supporting means, a contact supporting member movably carried by the yoke, a contact on said contact supporting member, a standard on the supporting means, a spring contact member on the standard, a contact carried by the 15 spring contact member and engageable with the first mentioned contact, and means carried by the spring contact member and engageable through the standard for limiting movement of the last mentioned contact away from the standard, said voltage coil being energizable from the alternating current source for floating the core within the coil in an oscillatory manner and vibrating the contacts at the frequency of the alternating current source, said spring contact 20 member permitting a lagging vibratory connection at the alternating current frequency between the contacts upon dropping of the voltage in the voltage coil so that the regulating means will be operative for increasing the voltage immediately to compensate for an increased load.

3. A voltage regulator including supporting means, a contact movably mounted on the supporting means, a standard on the supporting means, a spring contact member on the standard and having a contact, means adjustably connecting the last mentioned contact with the standard, said contacts being engageable in a vibratory manner, means for adjusting the tension of the spring contact member whereby the response of the contacts may be controlled, and voltage responsive means on the supporting means and being connected with the first mentioned contact.

4. In a voltage regulator, a base, a yoke on the base, a contact supporting member movably mounted in the yoke and having arms, a contact carried by one of the arms, a voltage coil carried by the base, a solenoid plunger movable in the voltage coil and being connected with the other of the arms of the contact supporting member, a standard on the base, a spring contact member on the standard and having a contact, means adjustably connecting a portion of the spring contact member and the second mentioned contact with the standard, said contacts being engageable in a vibratory manner, and means on the standard and engageable with the spring contact member for adjusting the tension of said spring contact member whereby the speed of vibratory engagement of the contacts may be controlled, said contacts being engageable at the speed of the frequency of an alternating current source energizing the voltage coil.

MICHAEL DEBREY. 65
